UNITED STATES PATENT OFFICE

2,448,955

METHOD AND APPARATUS FOR MEASURING PERMEABILITY

William A. Bruce, Tulsa, Okla., assignor to Standard Oil Development Company, a corporation of Delaware

Application June 1, 1945, Serial No. 597,016

2 Claims. (Cl. 73—38)

1

The present invention is directed to a method and apparatus for the determination of the permeability of rock cores and other consolidated porous bodies.

The principal object of the present invention is the provision of a method and apparatus by use of which the permeability of a core obtained during the drilling of a well, or in any other manner, may be approximated rapidly and on the spot.

In essence, the method of the present invention consists in affixing to the core in any suitable manner a suction device, building up a vacuum on the surface of the core and then observing over a predetermined period the decrease of the vacuum.

The nature of the present invention may be more clearly understood from the following detailed description of the accompanying drawing, which is a vertical section of one type of apparatus suitable for the practice of the present invention.

Referring to the drawing in detail 1 designates a container in which is deposited a bed 2 of loose fine sand, or other highly permeable material. Extending through the core 3 of the container is a pump 4 which is simply a cylinder provided with a piston 5 and a stem 6 having a handle 7. Affixed to the cylinder at a point below the uppermost point of travel of the piston is a pressure gauge 8. The lower part of the cylinder is provided with a plug 9 of soft rubber having a central passage 10.

In the use of this apparatus a core fragment 11 having a substantially flat surface is selected. The plug 9 is pressed against the flat surface and a layer of rubber cement 12 is applied to the flat surface in such a way to seal the lower end of the cylinder to the flat surface. It may be mentioned here that the core fragment is preliminarily treated to remove most of any liquid which it may have contained. This may be done conveniently by placing the core fragment in a suitable centrifuge for the removal of liquid.

In the actual field practice of this method it is not necessary to use the container 1. It is sufficient to substitute for the rubber cement a soft rubber disc which can be pressed against the core sample by the operator handling the sample in one hand and the pump in the other hand. Where possible, it is more convenient to use the assembly shown in the drawing.

2

When the core sample is properly affixed to the pump as shown in the drawing, the piston is pulled upwardly to a point above the pressure gauge to apply suction to the core. The reading in the pressure gauge at the end of the stroke is observed. It is again read at five second intervals, until the pressure returns to atmospheric, or to any predetermined value below atmospheric. This increase in pressure after the vertical stroke will 10 be due to the passage of air into the core from the exterior. The rate at which the pressure builds up will be a direct function of the permeability of the core sample. This reading can be taken as an approximation of the permeability 15 of the material of which the core is constituted.

The nature and objects of the present invention having been thus described and illustrated, what is claimed as new and useful and is desired to be secured by Letters Patent is:

20 1. A method for determining the permeability of a rock core from a fragment thereof which comprises selecting a fragment of said core of irregular configuration having at least one substantially flat face, arranging said fragment in 25 a bed of loose particles with said substantially flat face exposed, building up a vacuum on said substantially flat face and observing the rate at which said vacuum is dissipated.

2. A device for determining the permeability 30 of a consolidated porous body comprising a tubular pump having a reciprocating plunger, a layer of soft, conformable, impervious material attached to the suction end of said pump and arranged around the intake thereof in such a manner that 35 said layer can be pressed against said porous body to form a seal on said body around the intake end of said pump and a pressure gauge connected to said pump at a point between its intake and the point designating the end of the plunger stroke.

40 WILLIAM A. BRUCE.
